UNITED STATES PATENT OFFICE.

CHARLES SCHOFIELD ROBERTSHAW, OF NATCHITOCHES, LOUISIANA.

WATCH-PROTECTING DEVICE.

1,300,024.

Specification of Letters Patent.

Patented Apr. 8, 1919.

Application filed April 2, 1918. Serial No. 226,199.

To all whom it may concern:

Be it known that I, CHARLES S. ROBERTSHAW, a citizen of the United States, residing at Natchitoches, in the parish of Natchitoches and State of Louisiana, have invented new and useful Improvements in Watch-Protecting Devices, of which the following is a specification.

This invention relates to watch protecting devices, and the object is to provide means for retaining a watch in the pocket of the wearer, without the necessity of attaching the watch to any object and without causing delay in inserting the watch into the pocket or withdrawing it therefrom.

A further object is to provide a protecting device comprising a light metallic plate to be placed inside of the pocket and secured by means of suitable fastening devices, this plate being provided with adjustably mounted tongues of resilient material, which tongues engage the watch when it is inserted, and permit of the removal thereof by a slight pull, the engaging devices then resuming their normal position.

A still further object is to provide a protecting device comprising a plate carrying means for cushioning the watch, and means for engaging the latter in order to prevent the accidental loss of the watch from the pocket, the engaging means comprising a plurality of resilient devices slidably longitudinally within a guiding slot and adapted to engage portions of the watch and prevent the accidental displacement of the latter from the pocket.

With the foregoing and other objects in view the invention consists in the novel construction, combination, and arrangement of elements hereinafter described and claimed.

In the drawings,

Figure 1 is a view showing the device, partly in dotted lines, and partly in full line elevation, as applied to the pocket;

Fig. 2 is a vertical transverse section;

Fig. 3 is a similar section, with the watch in position;

Fig. 4 is a face view of the device detached from the pocket.

In carrying out my invention I employ a plate member of suitable size and stamped from sheet aluminum, this plate member being designated 10 and provided with a rectangular opening near one upper corner,

this opening being shown at 12. Longitudinal slot 14 communicates with opening 12

and is adapted to receive a plurality of devices formed of rubber, these devices being designated tongues and shown at 15. They are provided with flattened heads 16 and 60 with grooves 17 in the shank portion near the head for engaging the edge portions of the slots. They may be moved to the required position in the slot for engaging the upper portion of the casing of the watch adjacent to the stem.

The plate is secured by means of fastening devices or hooks designated 18 and including teeth 19 and bill portion 20. These fastening devices are suitably secured to the 70 plate near the end thereof and engage the cloth of the garment in the manner shown, for the purpose of retaining the plate in position.

Longitudinal slots 22 and 23 are also provided in the plate and within these slots are secured in any suitable manner strips of rubber, felt, or cork, for the purpose of preventing the scratching or abrasion of the watch case.

Watches of various sizes are accommodated by simply adjusting the rubber tongues within the slot 14. Two of these tongues are usually sufficient but additional tongues may be provided if desired. The 85 fastening devices may be enameled to correspond with the color of the clothing, and the protecting devices may be sold with various colors of attaching devices if desired. However, this is only a minor point and is 90 merely mentioned in order to show how the device may be adapted to the whims of the purchaser. The cost of manufacture will be very low, the device is practically indestructible and cannot get out of order, and is 95 useful alike to athletes and to travelers, as well as to individuals in general.

What is claimed is:

1. In a device of the class described, a plate member, securing means therefor, and a plurality of watch engaging devices slidably mounted on the plate and having frictional engagement with said plate.

2. In a device of the class described, a plate member, means for securing the latter within the pocket of the garment, and a plurality of resilient and slidably mounted watch engaging devices, carried by the plate and having frictional engagement with said plate.

3. In a device of the class described, a plate member provided with a longitudinal

slot and adjustably mounted members of resilient material engaging the edges of the slot and spaced apart.

4. In a device of the class described, a plate member provided with a longitudinal slot having an enlarged portion at one end, a plurality of resilient devices extending through the slot and each including a shank portion and a head, and means for securing 10 the plate member within a pocket.

5. In a device of the class described, a plate member provided with a longitudinal slot, resilient devices mounted within said slot, and adjustable with reference to each other, additional slots being formed within 15 said plate, and cushioning means mounted within the slots last named.

In testimony whereof I affix my signature.

CHARLES SCHOFIELD ROBERTSHAW.
